UNITED STATES PATENT OFFICE.

ROBERT R. TICHENOR AND PHILETUS WALKER, OF HENNING, MINNESOTA.

WAGON END-GATE.

SPECIFICATION forming part of Letters Patent No. 369,894, dated September 13, 1887.

Application filed January 19, 1887. Serial No. 224,759. (No model.)

To all whom it may concern:

Be it known that we, ROBERT R. TICHENOR and PHILETUS WALKER, both of Henning, in the county of Otter Tail and State of Minnesota, have invented a new and Improved 5 Wagon-Box End-Gate, of which the following is a specification, reference being had to the annexed drawings, forming a part thereof, in which—

10 Figure 1 is an end elevation of a wagon-box to which our improved end-gate has been applied. Fig. 2 is a horizontal section taken on line $\alpha\alpha$ in Fig. 1, and Fig. 3 is a detail perspective view of the end-gate removed from the box.

15 Similar letters of reference indicate corresponding parts in all the views.

The object of our invention is to provide an 20 effective end-gate which may be readily removed and replaced in the wagon-box and which will securely bind the ends of the side-boards of the box.

Our invention consists in the construction 25 and arrangement of parts, as will be hereinafter fully described and claimed.

To the inner surface of the side-boards A A' of the wagon-box B, near their rear ends, are secured the angle-plates a a', provided with the inwardly-projecting flanges b b'. Each 30 plate is furnished with two apertures, c, for receiving the fastening devices of the end-gate C, also with a threaded shank, which extends through the bottom and cleat of the box and receives a nut.

35 To the outer surface of the end-gate C, near one end, is secured a plate, D, provided with a rearwardly-projecting flange, d, which abuts against the angle-plate a. The said plate is also provided with the hooks e, which are 40 adapted to enter into the apertures c of the plate a. To the rear side of the end-gate C, near the opposite end, is secured a plate, E, having ears f projecting rearwardly therefrom, in which is pivoted a crank-rod, g. On the 45 rod g is pivoted a forked lever, F, having at

the extremities of its two arms hooks h, adapted to enter into the apertures c of the plate a'. The opposite end of the forked lever is provided with an arm, i, and to the rear surface of the end-gate C is secured a plate, j, 50 to which is pivoted a button, k, capable of engaging the arm i.

The end-gate is put in position in the wagon-box by inserting the hooks e in the apertures c of the plate a, then while the lever F is swung outward inserting the hooks h in the apertures c of the angle-plate a', then swinging the lever toward the end-gate C. The swinging of the lever turns the crank-rod g in its supports and draws the side-boards toward each other, 60 bringing them into close contact with the ends of the end-gate. The final movement of the arm i of the lever F toward the end-gate clamps the end-gate firmly against the flange b of the angle-plate a'. When the arm i is 65 in contact with the end-gate, the button k is allowed to fall over the arm, thus securing the lever F.

Having thus fully described our invention, we claim as new and desire to secure by Letters Patent—

The combination, with the end-gate C, of the apertured plates a a', secured to the side-boards of the wagon, and formed with the flanges b b' on their rear edges and with 75 threaded shanks on their lower ends extending through the bottom of the wagon and having nuts thereon, the plate D, provided with the hooks e, the crank-rod g, pivotally connected with the end-gate, the forked lever F, 80 provided with hooks h, mounted pivotally on the crank-rod g and adapted to engage the apertured plate a', and means, substantially as shown and described, for fastening the lever F.

ROBERT R. TICHENOR.
PHILETUS WALKER.
